ATTORNEYS

UNITED STATES PATENT OFFICE.

EMIL STOHN, OF JERSEY CITY, NEW JERSEY.

DESIGN FOR A PATTERN FOR CLOTH.

SPECIFICATION forming part of Design No. 27,029, dated May 4, 1897.

Application filed March 5, 1897. Serial No. 626,139. Term of patent 3 $\frac{1}{2}$ years.

To all whom it may concern:

Be it known that I, EMIL STOHN, a citizen of the United States, residing at Jersey City, in the county of Hudson and State of New Jersey, have invented and produced a new and original Design for Cloth-Patterns, of which the following is a specification.

The design consists of a cloth-pattern composed of ornamental radiating or divergent portions variously shaped and having foliate or leaf-shaped ornamentations.

The design is illustrated in the annexed drawing, illustrating a plan view of the pattern on a piece of cloth.

15 One set of ornamentations comprises radiating or divergent arms 1 2 and 1 3. The arm or branch 1 2 is curved and provided with leaf-shaped or pointed ornamentations 4. The arm or branch 1 3 has similar ornamentations 5. The arm or branch 6 7 has the pointed ornamentations 8, and the arm or branch 9 10 has the pointed ornamentations 11, as also a supplemental branch 12, provided with a foliate or leaf-shaped ornamentation 13 14.

25 The other set of ornamentations comprises radiating or divergent arms or branches, one of which is shown at 15 16 17, having an angle shape, while another branch 15 18 has 30 pointed ornamentation 19, another branch 15 20 having pointed ornamentations 21, and branches 15 35 are forked or shown with divergent pointed end portions.

The next succeeding set or row of ornamentations may be considered as the reverse of 35 the ornamentations first described, the curved branch 22 23, with foliations 24, corresponding to reversed branch 1 2 of said first-named ornamentation. Branch 22 25, with foliations 26, similarly corresponds to branch 1 3, while 40 branch 27 28, with foliations 29, similarly corresponds to branch 6 7, and branch 30 31, with foliations 32, and supplemental branch 33, with foliation 34, corresponds to branch 9 10.

The next succeeding set of ornamentations 45 may be considered as the reverse of the second-named set of ornamentations 15 17 18 35, while the next succeeding set of ornamentations are reproductions of the first-named ornamentations. The background or body of 50 the cloth is faced or provided with longitudinal parallel lines 36.

The design gives a striking and characteristic appearance.

What I claim as new, and desire to secure 55 by Letters Patent, is—

The design for a cloth-pattern as herein shown and described.

In testimony whereof I have hereunto set my hand in the presence of two subscribing 60 witnesses.

EMIL STOHN.
